UNITED STATES PATENT OFFICE.

JAMES T. ANTHONY, OF EAST ORANGE, NEW JERSEY, ASSIGNOR TO AMERICAN ARCH COMPANY, OF NEW YORK, N. Y., A CORPORATION OF DELAWARE.

STEAM-LOCOMOTIVE.

1,229,383.

Specification of Letters Patent. Patented June 12, 1917.

Application filed February 8, 1916. Serial No. 76,947.

To all whom it may concern:

Be it known that I, JAMES T. ANTHONY, a citizen of the United States, and a resident of East Orange, county of Essex, and State 5 of New Jersey, have invented certain new and useful Improvements in Steam-Locomotives, of which the following is a specification.

My invention relates to steam railroad locomotives and has special reference to improvements in the boilers thereof.

The immediate purpose of my invention is to increase the capacity and efficiency of the boilers of locomotives of the Mallet, Santa 15 Fe, Mikado, Atlantic and Pacific types.

The general object of my invention is to provide for the economical construction and maintenance of still larger locomotives, and to enable them to be operated with equal or 20 greater efficiency.

The principle and broad characteristics of my invention, and also the details thereof, will be readily understood on reference to the drawings which form part of this specification, in which I have shown my invention in the best form that I have thus far devised.

In said drawings, Figure 1 is a vertical, longitudinal section of a steam railroad locomotive embodying my invention;—Fig. 2 is a horizontal section on the line X—X of Fig. 1;—Fig. 3 is a vertical transverse section on the line Y—Y of Fig. 1;—Fig. 4 is a vertical section on the line Z—Z of Fig. 1;—Fig. 5 is a vertical section on the line W—W of Fig. 1;—Fig. 6 is a side elevation of the rear end of the locomotive;—Fig. 7 is a plan view of the mud ring of my novel boiler;—and Fig. 8 is a plan view of a modified form 40 of said mud ring.

The drawings illustrate what is known as a 2—10—2 type of locomotive, the same having five coupled drivers on each side, a two-wheeled pony truck, 3, at the forward end; 45 and a two-wheeled trailer truck, 4, at the rear end. As usual, the main frames, 5, are arranged between the drivers, 2, and the trailer truck, 4, is held by trailer frames, 5', that are lower than the main frames, 5, to 50 which they are spliced.

It is sufficient to recall that the use of the trailer truck and a low frame therefor permits the use of a boiler firebox which extends laterally beyond the vertical planes of 55 the main frames and drivers, and has its

grate below the level of the tops of the drivers. This is a measure adopted to secure a grate area adequate to the boilers of locomotives of the large types above mentioned, and I retain this feature for the same reason; 60 also because the trailer construction admits an ash pan 6, (diagrammatically shown herein) of simple form, without the complications and axle-housings typical of wide fireboxes of the old type, disposed above the 65 drivers.

The parts of the novel boiler shown in the drawings are as follows:—

7, is the main shell or barrel of the boiler.

7^a, is the steam dome.

8, is the front flue sheet.

9, are the boiler flues.

10, is the "front end" or smoke box; and, 10^a the smoke stack.

11, is the boiler breast or outside throat sheet.

12, 13, 14 and 15 are component parts of the firebox shell or wrapper sheet.

16, is the rear sheet of the boiler or firebox shell.

17, is the rear or firebox flue sheet, and 80 17' is the inside throat sheet, being an extension of the flue sheet.

18, 19 and 20 are the component parts of each firebox side sheet.

21, is the crown sheet.

22, is the rear sheet of the firebox.

23, 24, 25, 26, 27 and 28 are component parts of the boiler or firebox mud ring.

29, 30 and 31 are transversely arranged 90 sheets which join the side sheets of the firebox.

32, is the grate of the firebox.

33, is a floor-plate, attached preferably to the parts 23, 24, and 25 of the mud ring.

34, is a man-hole in the floor-plate, 33.

35, is a tight, drop cover or closure for the man-hole.

36, is a firebrick lining which protects the floor-plate, 33.

37, are inclined water-circulating arch-tubes which extend from the plates, 19, to the upper part of the rear sheet, 22.

37', are like arch-tubes, which extend from the sheet, 29, to the upper part of the rear sheet, 22.

38, are clean-out openings and plugs in the sheets, 14, for the arch-tubes, 37.

38', are clean-out openings and plugs in the sheet, 30, for the arch tubes, 37'. 110

38", are openings and plugs in the rear sheet, 16, which afford access to the upper ends of respective arch tubes.

39, 39 are the fuel door openings and 5 doors in the rear end of the firebox.

E, is the fire-chamber;—F, is the combustion chamber;—and G, is a passage above the water leg or cross wall, by which the chambers, E and F are placed in communication. The lower part, F', of the chamber, F, constitutes a cinder accumulation pocket and also provides space for a superheater or a feed water heater, shown by dotted lines, H, in Fig. 1.

15 It is to be understood that the lower edges of the plates, 11, 17', 20, 15, 30, 29, 14, 19, 13, 18, 22, and 16 are attached to respective parts of the mud ring.

A, B and C are the transverse water legs 20 of the boiler, and, D, D, are longitudinal, or side, water legs of the boiler.

It is to be understood that all opposed walls of the firebox and firebox shell are united by stay-bolts, 40, in the usual manner. Special attention is directed to the stay-bolts, 40', which unite the opposed walls, 29, 30, of the intermediate water-leg or fire-wall, B.

The outer ends of the transverse water 30 leg, B, are in free communication with the side water legs, D. The top, 31, of the water leg, B, is lowest at its middle point and curves upwardly from thence to points of juncture with the side sheets of the firebox. I prefer that the top line of the wall, B, shall be substantially a continuation of the curves of the adjoining walls of the firebox. This construction of the top of the water leg, B, and the direct opening thereof 40 into the side legs, prevents the trapping and pocketing of steam in the water leg, B. Obviously the water leg, B, provides an admirable source of water supply for all the arch tubes which lead from it, and the flow of 45 water in the tubes further promotes circulation in both the side legs and the cross leg of the boiler.

It will be noted that the water leg, B, joins the sides of the firebox substantially 50 at the points of juncture between the wide and narrow portions of the firebox. It thus provides an admirable connection between the boiler sides and, in conjunction with the cross member or bridge, 25, of the firebox 55 base or mud ring, effectually holds them in correct shape against all forces tending to distort them.

As shown, the throat, A, of the boiler is 60 of such depth that it extends downward practically to the tops of the engine frames, 5. The forward section of the mud ring, and hence the lower forward part of the firebox, conforms to the throat, A, and occupies the space between the opposite drivers, 2. Obviously by further narrowing the 65

lower front end of the firebox, it may be positioned between the engine frames, 5, but in most cases the construction shown will be found to yield better results.

The narrow forward section of the mud 70 ring extends from the throat sheets to a point rearward of the rearmost driver; that is, to a point where the flaring parts may clear the drivers. The rear section of the mud ring and firebox not being restricted 75 or limited in width by the engine frame, may be extended laterally to any practical extent. The height of the rear section of the mud ring above the rails, and its inclination, may also be varied within wide limits, 80 as deemed best by the designer. This rear section which contains the grate, 32, carries the ash pan, 6. To the novel mud ring here shown and which dominates the form and construction of the novel firebox, I have 85 given the name "sectional mud ring." As clearly shown, the mud ring is composed of two substantially rectangular portions joined end to end and having the cross bar, 25, in common.

90 My invention is not restricted to a mud ring of the specific shape above described, for, as indicated in Fig. 8, the shape of the ring may be modified by giving it a more rectangular configuration to suit a combination firebox in which the juncture plates, 42, are substantially at right angles to the remainder of side sheets of the boiler. Likewise I wish it to be understood that the term "rectangular" as used in the specification and appended claims is intended to embrace sectional mud rings having members which are variously curved and angled.

95 I desire that it shall be understood that in some cases the integral bridge bar, 25, of 105 the mud ring, or a separate bridge-member located at that point, may be used in conjunction with a water-wall separate from the side sheets or with a refractory brick fire-wall in lieu of the illustrated wall, B. 110 While my invention embraces these modifications, I regard the construction shown as far preferable thereto.

The man-hole, 34, which is normally 115 tightly closed by a door or cover plate, 35, affords easy access to the combustion chamber, F. This is of great advantage in working upon the flues and flue sheet of the boiler, and the arch tubes and other parts exposed in the chamber, F. Obviously all 120 such work may be done in the chamber, F, without hindrance by the ordinarily hot firebox arch, which in other constructions is an obstacle that must be wholly or at least partly removed at such times.

To my novel firebox, considered as a 125 whole, I have given the alternative names combination firebox and combined wide-and-narrow firebox.

130 My invention will be found most advan-

tageous where the fuel is supplied by mechanical stokers and where pulverized coal is blown into the firebox with a blast of air. In most cases much of the coal is burned in suspension and the long flame-way here provided insures a degree of combustion not attainable in other locomotive fireboxes.

The many other advantages of my invention will be manifest to those who are skilled in the art. For example, (1) the great increase in firebox volume, the marked increase in the length of the flame-way, and the ample combustion space provided;—(2) the augmenting of circulation in the boiler;—(3) the retention of the boiler as an entirety in a desirable low position over the drivers;—(4) the nice distribution of weight upon the drivers consequent upon the construction of the boiler in the manner described;—(5) the ease and certainty with which the component sheets of the firebox may be assembled and their joints maintained;—(6) the ease with which the parts of the boiler shell and firebox may be stayed;—(7) the removal of the flue sheet from the proximity of the grate;—(8) the cutting down of the hitherto excessive length of the flues of high-power locomotives;—(9) the practicability of either lengthening or shortening the fire-chamber and grate, when desired, without detrimentally reducing the flame-way, and without necessitating the lengthening of the flues;—(10) the replacement of inefficient flue heating-surface by highly efficient firebox heating-surface;—(11) the ability to use flues of such short length as to be of assured heating value and of assured benefit to a superheater installed in connection therewith;—(12) the addition of firebox heating surface by the use of the intermediate water leg; (13) and, the ease with which arch tubes and arches may be installed and maintained.

Many obvious modifications of my invention will readily suggest themselves to one who is skilled in the art, and I do not limit the invention to the specific constructions herein shown and described.

Having thus described my invention, I claim as new and desire to secure by Letters Patent:—

1. The improvement herein described comprising a mud ring composed of two sections arranged end to end and one narrower than the other.

2. The improvement herein described comprising a mud ring composed of two sections arranged end to end and one narrower than the other, there being an intermediate cross bar which is common to both sections.

3. The improvement herein described comprising a mud ring composed of two sections arranged end to end and one narrower than the other, there being an intermediate cross

bar which is common to both sections, and said cross bar being of greater width than the other parts of the mud ring.

4. The improvement herein described comprising a locomotive mud ring composed of a narrow front section of substantially rectangular form and a substantially rectangular wide rear section integral with said front section.

5. The improvement herein described comprising a locomotive mud ring composed of a narrow front section of substantially rectangular form and a substantially rectangular wide rear section integral with said front section, and said sections together forming an obtuse angle.

6. The improvement herein described comprising a locomotive firebox mud ring composed of a front section and a rear section wider than said front section there being an intermediate cross-bar portion common to said front and rear section, and the sides of said rear section merging into the sides of the front section upon obtuse angles.

7. The improvement herein described comprising a combined wide-and-narrow firebox, in combination with respectively wide and narrow mud rings for the sections or portions thereof, a grate in the bottom of the wide portion thereof, and a floor closing the bottom of the narrow portion thereof.

8. The improvement herein described comprising a combined wide-and-narrow firebox, in combination with respectively wide and narrow mud rings for the sections or portions thereof, a grate in the bottom of the wide portion thereof, a floor-plate closing the bottom of the narrow section, and said floor-plate containing a normally closed man-hole.

9. The improvement herein described comprising a combined wide-and-narrow firebox, in combination with respectively wide and narrow mud rings for the sections or portions thereof, a grate in the bottom of the wide portion thereof, a floor-plate closing the bottom of the narrow portion, and a fire wall erected between said portions.

10. The improvement herein described comprising a combined wide-and-narrow firebox, in combination with respectively wide and narrow mud rings for the sections or portions thereof, a grate in the bottom of the wide portion thereof, a floor-plate closing the bottom of the narrow portion, a fire wall upstanding at the juncture of said portion, and said floor-plate containing a normally closed man-hole.

11. The improvement herein described comprising a combined wide-and-narrow boiler and firebox, in combination with respectively wide and narrow mud rings for the sections or portions thereof, a closure in the bottom of the wide portion thereof, a closure in the bottom of the narrow portion,

tion thereof, a water wall erected between said portions, and arch tubes having their ends in said wall.

12. The improvement herein described comprising a combined wide-and-narrow boiler and firebox, in combination with respectively wide and narrow mud rings for the sections or portions thereof, a closure in the bottom of the wide portion thereof, a closure in the bottom of the narrow portion thereof, a water wall rising between said portions at the juncture thereof, and water circulating arch tubes extending from said wall across said wide portion.

13. The improvement herein described comprising a combined wide-and-narrow firebox, in combination with respectively wide and narrow mud rings for the sections or portions thereof, a closure in the bottom of the wide portion thereof, a closure in the bottom of the narrow portion thereof, a cross bar between said closures and joining the sides of the firebox.

14. The improvement herein described comprising a combined wide-and-narrow firebox, in combination with a closure in the bottom of the side portion thereof, a closure in the bottom of the narrow portion thereof, a cross bar between said closures and joining the sides of the firebox, and a transverse water leg erected on said cross bar.

15. The improvement herein described comprising a combined wide-and-narrow firebox, in combination with respectively wide and narrow mud rings for the sections or portions thereof, a closure in the bottom of the wide portion thereof, a closure in the bottom of the narrow portion thereof, a cross bar between said closures and joining the sides of the firebox, a transverse water leg erected on said cross bar, and arch tubes extending from said leg to the opposite end of said wide portion of the firebox.

16. The improvement herein described comprising a locomotive boiler containing a wide bottomed firebox section and a narrow bottomed combustion chamber section in communication therewith, and a mud ring having respectively wide and narrow portions conformed to the bottoms of said sections.

17. The improvement herein described comprising a locomotive boiler containing a wide bottomed firebox section and a narrow bottomed combustion chamber section in communication therewith, and a mud ring having respectively wide and narrow portions conformed to the bottoms of said sections and connecting the sides thereof.

18. The improvement herein described comprising a locomotive boiler containing a wide bottomed firebox section and a narrow bottomed combustion chamber section in communication therewith, a mud ring having respectively wide and narrow portions

conformed to the bottoms of said sections, and said mud ring having a cross bar positioned at the point of juncture between said sections.

19. The improvements herein described comprising a locomotive boiler containing a wide bottomed firebox section and a narrow bottomed combustion chamber section in communication therewith, a mud ring having respectively wide and narrow portions conformed to the bottoms of said sections, said mud ring having a cross bar positioned at the point of juncture between said sections, and a transverse water leg bottomed by said cross bar and connecting the side water legs of the boiler.

20. The improvements herein described comprising a locomotive boiler containing a wide bottomed firebox section and a narrow bottomed combustion chamber section in communication therewith, a mud ring having respectively wide and narrow portions conformed to the bottoms of said sections, said mud ring having a cross bar positioned at the point of juncture between said sections, a transverse water leg bottomed by said cross bar and connecting the side water legs of the boiler, and arch tubes extending from the said leg to the opposite end of the firebox section.

21. The improvement herein described comprising a locomotive boiler containing a wide bottomed firebox section and a narrow bottomed combustion chamber section in communication therewith, a mud ring having respectively wide and narrow portions conformed to the bottoms of said sections, said mud ring having a cross bar positioned at the point of juncture between said sections, a transverse water leg bottomed by said cross bar and connecting the side water legs of the boiler, arch tubes extending from the said leg to the opposite end of the firebox section, and clean-out openings in said leg for said tubes.

22. A steam locomotive, the boiler of which contains a fire-chamber rearward of and below the tops of the drivers and having a grate which is wider than the span of the drivers, in combination with a combustion chamber, the lower part of which extends below the tops of the drivers and is of less width than the space between said drivers and a floor plate closing the otherwise open bottom of said combustion chamber.

23. A steam locomotive, the boiler of which contains a fire-chamber rearward of and below the tops of the drivers and having a grate which is wider than the span of the drivers, in combination with a combustion chamber, the lower part of which extends below the tops of the drivers and is of less width than the space between said drivers, and a floor plate closing the other- 130

wise open bottom of said combustion chamber, and said boiler also containing a transverse water leg between said chambers.

24. A steam locomotive, the boiler of which contains a fire-chamber rearward of and below the tops of the drivers, and having a grate which is wider than the span of the drivers, in combination with a combustion chamber, the lower part of which extends below the tops of the drivers and is

of less width than the space between said drivers, said boiler also containing a transverse water leg between said chambers, a floor plate closing the otherwise open bottom of the combustion chamber, and there being a man-hole in said floor plate or bottom of said combustion chamber.

In testimony whereof, I have hereunto set my hand this 31 day of January, 1916.

JAMES T. ANTHONY.
